STRIKER PLATE

Luther A. Menges, Detroit, Mich., assignor to
 Chrysler Corporation, Detroit, Mich., a corpora-
 tion of Delaware

Application October 28, 1933, Serial No. 695,567

5 Claims. (Cl. 292—340)

This invention relates to an improved striker plate and particularly to a device of this character for co-operating with the latch bolt of a vehicle door.

5 The main objects of the invention are to provide resilient means in a striker plate for cushioning the action of the latch bolt with which it co-operates during latching operation; and to provide resilient means of this character which 10 has sound insulating properties for interrupting the direct transmission of sound vibrations to the structure on which the striker plate is mounted and deadening the noise resulting from engagement and disengagement of the latch bolt 15 and striker plate.

Other objects of the invention are to provide a striker plate having a rubber backing adjacent the structure on which it is mounted and an exposed wear resisting element for engaging the 20 latch bolt; to provide a rubber backing which is securable to said structure and which is integrally bonded, preferably by vulcanization, to a wear 25 resisting element and to a fastening element; to provide a striker plate of this kind having more than one latch bolt receiving notch; to provide an aperture in the wear resisting element through which a portion of the backing is exposed to permit the latch bolt to engage directly with the 30 backing as the bolt is projected into the notch for cushioning the impact of the latch bolt; to provide a yieldable sound insulating backing which has a portion exposed adjacent each notch for receiving the impact of the latch bolt as the latter is projected hereinto; and to provide means 35 of this character for preventing metal-to-metal contact of the wear resisting element and the latch bolt as the latter snaps over the ramps or shoulders of the striker plate and into the associated notches.

40 Illustrative embodiment of the invention is shown in the accompanying drawing, in which:

Fig. 1 is a fragmentary horizontal sectional view of a door and associated door post structure showing a striker plate embodying the invention.

45 Fig. 2 is a plan view of the improved striker plate.

Fig. 3 is a longitudinal sectional view taken on the line III—III of Fig. 2.

50 Fig. 4 is a transverse sectional view taken on the line IV—IV of Fig. 2.

Fig. 5 is a transverse sectional view taken on the line V—V of Fig. 2.

55 Fig. 6 is a longitudinal sectional view similar to Fig. 3 but showing a modified form of the invention.

In the form shown in Figs. 1 to 5, inclusive, my improved striker plate includes a yieldable body portion 11 which preferably comprises sound insulating material such as relatively soft rubber. A fastening plate 12 preferably formed of 5 brass, brass coated ferrous metal, or other suitable rigid material to which rubber readily bonds during vulcanization, is integrally bonded by vulcanization to the left side of the body portion 11, as viewed in Fig. 1. The fastening plate 12 is 10 provided with spaced apertures 13 and 13' which register with apertures 14 and 14' formed in the body portion 11 for receiving screws 15 and 15' respectively, or other suitable fastening means by which the striker plate is rigidly secured to a 15 door post 16 or other structure similarly located, with respect to a door 17.

Formed in the opposite side of the body portion 11 of the striker plate is a pair of notches or depressions 18 and 19. Shoulders 20 and 21 are 20 provided adjacent each notch 18 and 19 respectively, and ramps 22 and 23 are provided on the right side of the striker plate adjacent the shoulders 20 and 21 respectively.

A wear resisting element 24 which conforms 25 to the shape of the notched side of the body portion 11 is mounted on the latter and preferably integrally bonded thereto by vulcanization. This wear resisting element has an edge portion 24' adjacent the shoulders 20 beyond which a flange 30 30 of the body portion 11 extends. An aperture 26 is formed in that part of the wear resisting element which registers with the ramp 22 of the body portion 11 and with the aperture 14' of the latter. The aperture 26 is substantially larger 35 than the aperture 14' and it permits the insertion of the screw 15' through the aperture 13' of the fastening plate 12 from the right side of the striker plate. A protuberance 27 formed on the body portion 11 extends through the aperture 40 26. That portion of the wear resisting element 24 which registers with the ramp 23 of the body portion is provided with an aperture 28 for accommodating the screw 15.

45 My improved striker plate may be used to advantage in conjunction with substantially any conventional latch apparatus of the character shown in Fig. 1 which, for the purpose of illustration, includes a latch bolt 29 slidably mounted in the door structure 17. The latch bolt 29 is 50 normally urged outwardly by a spring 30 against the action of which it may be retracted by turning a handle 31, journaled in the door structure 17, in a clockwise direction. The door handle 31 has a stem 32 extending into the door structure 5

and provided on its inner end with a cam 33 which bears against a shoulder 34 formed on the latch bolt 29.

In operation, as the door 17 is moved toward its closed position, the rounded outer extremity of the latch bolt engages the wear plate 24 at the first ramp 23, and further closing movement of the door causes the latch bolt to be urged inwardly against the action of the spring 30 until the bolt passes over the shoulder 21. When the latch bolt reaches this position it is projected outwardly by the spring 30 and into the first notch 19 of the striker plate. The protuberance 27 of the body portion 11 of the striker plate receives the impact of the latch bolt as it is projected into the notch 19, and prevents metal-to-metal contact of the extremity of the latch bolt with the wear plate, and thereby eliminates the creation of objectionable noise during the first stages of the door closing operation. Further closing movement of the door causes the latch bolt to be retracted against the action of the spring 30 by the second ramp 22, and when the door has reached its fully closed position the latch bolt is then projected by the spring 30 into the second notch 18. During this movement of the latch bolt, the impact thereof is cushioned by the flange 25 of the body portion 11 which protrudes beyond the shoulder 20 and edge portion 24' of the wear plate adjacent thereto.

In the form shown in Fig. 6, my improved striker plate includes a rubber body portion 11' having a metal attaching plate 12' rigidly bonded, preferably by vulcanization, to one of its sides and a metal wear plate 24' similarly attached to its opposite side. The body portion 11' is of substantially the same shape as the body portion 11 of the device shown in Figs. 1 to 5, inclusive, and the wear resisting plate 24' conforms with the contour of the side of the block on which it is mounted. The wear resisting plate 24' is provided with shoulders 20' and 21'. An aperture 26' formed in the plate 24' adjacent the shoulder 21' exposes the body portion 11' and accommodates an outwardly extending projection 27' thereof.

The attaching plate 12' has struck out flanges 40 and 41 embedded in the rubber body portion. The flange 40 is located slightly in advance of and in registration with an outwardly extending flange 42 on the wear resisting plate 24'. The flange 42 is also embedded in the rubber body portion and the flange 41 is located in advance of and in registration with the shoulder 21'. The flanges 40, 41 and 42 assist in holding the metal plates against movement relative to the rubber body portion of the device and provide a mechanical interlock between the two metal plates which will prevent the door from swinging open in the event of failure of the bond between the rubber and metal plates or failure of the rubber of which the body portion is formed. A part of the rubber body portion 11' extends beyond the shoulder 20' and provides a non-metallic seat for receiving the locking bolt after it passes over the shoulder 20'.

Cushioning of the impact of the latch bolt as the latter projects into the first and second notches of the striker plate eliminates much of the objectionable noise accompanying the closing of the vehicle doors equipped with conventional striker plates, and the provision of a substantially thick layer of yieldable sound insulating material between the wear resisting element of

the striker plate and the structure upon which the latter is mounted interrupts the transmission of sound vibrations from the wear resisting element to the door post or other structure, which in modern vehicles mainly comprises metal and acts as a sounding board. In this manner, amplification of the sound created by the metal-to-metal contact of the latch bolt and the wear resisting element is avoided.

Although but several specific embodiments of the invention are herein shown and described, it will be understood that various changes in the size, shape, and arrangement of parts may be made without departing from the spirit of my invention, and it is not intended to limit its scope other than by the terms of the appended claims.

What I claim is:

1. A striker comprising a rubber element, a backing plate secured to one side of said rubber element and having a flange embedded therein, the opposite side of said rubber element having a depression and an adjacent shoulder, a wear plate mounted on said shoulder, said plate having a portion thereof embedded in said rubber element in overlapping relation with the flange of said backing plate.

2. A striker comprising an apertured rubber body portion having an irregular surface, a wear resisting plate conforming to said irregular surface and bonded thereto, said plate having an aperture therein registering with the aperture of said rubber portion, a backing plate secured to the opposite side of said rubber body portion and having an aperture aligning with the apertures of said rubber body portion and said wear resisting plate, and means for securing said striker to a support, said means having a head portion spaced from said wear resisting plate and engaging said rubber body portion and said backing plate.

3. A striker comprising apertured metallic plates, one of said plates having latch bolt abutments thereon, an apertured rubber element disposed between and secured to the adjacent sides of said plates and having a portion thereof protruding beyond said plates and beyond one of said latch bolt abutments for receiving the extremity of a latch bolt, and means extending through said apertures for securing the structure to a support and having a head portion disposed entirely within the apertures of the rubber element.

4. A striker comprising a rubber element having formed on one side thereof a shoulder, a wear resisting plate mounted on said shoulder, and a plate bonded to the opposite side of said rubber element and having a flange embedded therein for assisting in holding said rubber element against displacement and deflection relative to said latter plate.

5. A strike for a latching element including an anchoring member, and a face plate adapted to be engaged by said latching element, a yieldable rubber body providing a union between said member and said face plate and adhesively secured to both said member and face plate, said member and said plate including portions disposed in relative opposition with the body providing a yieldable cushioning effect between said member and face plate, and aligned openings in said member, face plate and body to receive means for attaching the strike to a support.

LUTHER A. MENGES.
